1. This is a continuation-in-part of my original application for a patent filed on January 22, 1942, Serial No. 440,333, now abandoned, and to the claims of which reference is made. The present application is directed to the improvement of the apparatus set forth in the original application, and particularly to the provision of a more compact and convenient apparatus for the use of model vehicles.

UNITED STATES PATENT OFFICE

2,376,444

PORTABLE RACE TRACK

Broadus L. Mobley, Germantown, Tenn.

Application December 6, 1943, Serial No. 513,168

2 Claims. (Cl. 272—31)

The present invention relates to new and useful improvements in race tracks for captive, self-propelled model vehicles such, for example, as automobiles, motorcycles and power boats, and has for its primary object to provide, in a manner as hereinafter set forth, an apparatus of this character which is adapted to be expeditiously knocked down, transported to another location and again assembled or erected for operation.

Another very important object of the invention is to provide a portable race track of the aforementioned character comprising a novel construction and arrangement whereby two or more of the model vehicles may race in competition with each other rather than against time.

Still another very important object of the invention is to provide a portable model race track of the character set forth wherein, if desired, various types or kinds of vehicles may race in competition with each other.

Other objects of the invention are to provide a portable model race track which will be comparatively simple in construction, strong, durable, highly efficient and reliable in operation, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a portable model race track constructed in accordance with the present invention.

Figure 2 is a view in vertical section through a portion of the apparatus.

Figure 3 is a view in horizontal section through the apparatus.

Figure 4 is a detail view in vertical longitudinal section through the joint between two of the track sections.

Figure 5 is a view in horizontal section through the center post or shaft.

Figure 6 is a cross sectional view through one of the sectional skeleton arms.

Figure 7 is a perspective view of the bearing spacers showing said spacers separated.

Figure 8 is a perspective view of one of the supports at the lower end portion of the post on which it is mounted, showing said support and said post separated.

Figure 9 is a perspective view of the joint con-

struction between the track sections, showing the protecting plate separated.

Figure 10 is a fragmentary view in side elevation showing a slightly modified form of the invention.

Referring now to the drawings in detail, it will be seen that reference character 1 designates a metallic base. Mounted on the base 1 is a vertical shaft 2. Mounted for horizontal swinging movement on the shaft 2 at vertically spaced points are a plurality of sectional skeleton arms 3 of suitable metal. At their inner ends the arms 3 are provided with anti-friction bearings 4 which are journaled on the shaft 2. Spacing sleeves 5 are provided on the shaft 2 for the bearings 4. A retaining nut 6 is threaded on the upper end portion of the shaft 2.

Encircling the center shaft 6 in spaced, concentric relation thereto is a plurality of metallic posts 7. Metallic brackets 8 are detachably bolted to the posts 7 at vertically spaced points and project inwardly therefrom. Tubular radial rods 9 connect certain of the lowermost brackets 8 to the base 1. As illustrated to advantage in Figure 8 of the drawings, the brackets 8 comprise raised, comparatively high and low outer and inner end portions 10 and 11, respectively, with an arcuate intermediate portion 12 therebetween. The brackets 8 further include apertured flanges 13 to facilitate securing said brackets to the posts 7, the mounting of the track sections thereon, et cetera.

In the arrangement illustrated, banked circular tracks 14 are mounted on the lower and intermediate brackets 8, and a circular trough 15 of metal or other suitable material is mounted on the upper brackets 8. The tracks 14 include sections 16 of plywood, composition board or other suitable material which are secured upon the portions 10 and 11 of the brackets 8 by bolts 17 which pass through the openings in the end portions 10 and 11. As best seen in Figure 4 of the drawings, the upper surfaces of the end portions of the track sections 16 are beveled to accommodate protective plates or bars 18 which prevent splintering or splitting of said end portions of said track sections. The bolts 17 also secure the members 18 in position.

Self-propelled model vehicles such as automobiles and motorcycles 19 and 20, respectively, are operable on the banked tracks 14. The model vehicles 19 and 20 are hingedly mounted for vertical swinging movement only on the outer or free ends of the respective arms 3. The trough 15 is for the reception of water, as at 21, for floating

a model power boat 22. The boat 22 is hingedly mounted on the outer end of the uppermost arm 3. Extensions 23 are provided on the inner end portions 11 of the uppermost brackets 8 for the trough 15.

It is thought that the operation of the apparatus will be readily apparent from a consideration of the foregoing. Briefly, the self-propelled vehicles travel their respective circular courses to which they are confined by the arms 3 and the center shaft 2. As the vehicles are mounted on vertically spaced supports, one for each vehicle, said vehicles, racing in competition, are free to pass and repass each other at all times. The tracks 14 may be mounted on all of the brackets 15 and all of the competing vehicles may be model automobiles 19 or the model motorcycles 20. Or, if desired, the troughs 15 may be mounted on all of the brackets 8 in order that all of the competing vehicles may be the model power boats 22. Still further, the competing vehicles may be electrically driven and current may be supplied thereto in any suitable manner. In the slight modification shown in Figure 10 of the drawings, braces 24 extend between the brackets 8 beneath the end portions of the track sections 16 and the intermediate portions of said sections.

It is believed that the many advantages of a portable race track constructed in accordance with the present invention will be readily understood, and although a preferred embodiment of the apparatus is as illustrated and described, it is to be understood that changes in the details of construction and in the combination and arrangement of parts may be resorted to which will fall within the scope of the invention as claimed.

What is claimed is:

1. A race track of the character described comprising a base, a vertical shaft rising from the base, posts disposed vertically in a path encircling the shaft in spaced, concentric relation thereto, brackets mounted at vertically spaced points on the posts and projecting inwardly therefrom, each bracket having upstanding end portions provided with heads at their upper ends, circular tracks resting on the upstanding end portions of the brackets and secured to the heads thereof, arms journaled at vertically spaced points on the shaft for horizontal swinging movement about said shaft independent of and relative to each other, a sleeve about said shaft holding the arms in vertical spaced relation to each other, and model vehicles on the free ends of said arms operable on the tracks.
2. A race track of the character described comprising a vertical shaft, posts disposed vertically in a path encircling the shaft in spaced, concentric relation thereto, brackets mounted on the posts and projecting inwardly therefrom, each bracket having upstanding end portions and a downwardly bowed edge between the said end portions defining a recess, a circular trough for the reception of water seated in the recesses of said brackets with its side edges supported upon the said end portions of the brackets, an arm journaled on the shaft for swinging movement in a horizontal plane about the shaft and being of a length to dispose its free outer end over the brackets, and a model water craft mounted on the free end of said arm and operable in the water in the trough.

BROADUS L. MOBLEY.
